I. JAKLICH,

TABLE CASTER.

APPLICATION FILED NOV. 18, 1918.

1,293,788.

Patented Feb. 11, 1919.

UNITED STATES PATENT OFFICE.

IVAN JAKLICH, OF GARY, INDIANA.

TABLE-CASTER.

1,293,788.

Specification of Letters Patent. Patented Feb. 11, 1919.

Application filed November 18, 1918. Serial No. 263,076.

To all whom it may concern:

Be it known that I, IVAN JAKLICH, a subject of the Kingdom of Croatia, a part of Austria-Hungary, (having declared his intention to become a citizen of the United States of America,) residing at Gary, in the county of Lake and State of Indiana, have invented a certain new and useful Improvement in Table-Casters, of which the following is a specification.

This invention relates to table casters designed to contain a plurality of receptacles for a variety of articles or materials. The object of the invention is to provide a device of this class in which a plurality of the receptacles of the caster are provided with covers, said covers being connected with an automatic mechanism by which they may, at the will of the operator, be automatically 20 simultaneously opened for any purpose desired, such for instance as refilling the receptacles; this without destroying the ability of the user to independently open a single receptacle. The invention consists in mechanism for carrying out the foregoing objects; which can be easily and cheaply made and installed; which is satisfactory in operation, and is not readily liable to get out of order. The invention further consists in the features and details of construction which will be hereafter more fully set forth in the specification and claims.

Referring to the drawings, in which similar numerals indicate the same parts throughout the several views.

Figure 1 is a side view of a table caster equipped with the mechanism of this invention, everything of this device being shown.

Fig. 2 is a side view at right angles to that of Fig. 1, part of it being a central sectional view, and certain parts of the device which normally would be in the rear of Fig. 2 being omitted.

Fig. 3 is a plan view, somewhat enlarged, taken on the irregular line 3-3, of Fig. 2.

Fig. 4 is a sectional view through a portion of the caster base and a supporting leg therefor.

The caster of this invention is provided with six receptacles, two large bottles 10 and 12, suitable for instance for oil and vinegar; two shaker devices 14 and 16, suitable for instance for salt and pepper, and two other receptacles 18 and 20 suitable for instance for matches and toothpicks, all arranged about a central supporting post 22 rising

fixedly from a suitable base plate 24. The receptacles 10, 12, 14, and 16 are preferably adapted to enter and be retained in suitable recesses formed in the base 24, as illustrated 60 for instance in Fig. 2, wherein recesses 26 are shown.

Receptacles 10 and 12 are placed opposite to each other and are provided with stoppers 28 and 30 respectively, suspended upon lever arms 32 and 34, pivoted on vertical support 22 at 36 and drawn downward by the springs 38, clearly shown in Fig. 1. When the operator wishes to remove one of the bottles, as 10, he takes hold of the stopper device 28 and elevates it slightly against the action of the adjacent spring 38 until the stopper clears the top of the bottle, whereupon he can remove the bottle 10 for use in the ordinary way. To reinsert the bottle 10 75 in the caster, a reversal of the operation just described is carried out.

The central post 22, heretofore described, is surmounted by a convenient handle 40 within which reposes a push button 42 80 adapted by mechanism forming no part of this invention and therefore not shown, to, when depressed, move bell clapper 44 upward to strike the bell 46, mounted on the upper portion of the central post 22 and adjacent to the handle 40.

The salt and pepper receptacles 14 and 16 are normally covered and held in place in the caster by suitable cover members 50 and 52, pivoted at suitable points 54 and 56 adjacent 90 to the central post 22, these covers being held down upon the receptacles 14 and 16 by suitable springs 58 and 60, provided for the purpose.

Similarly, the receptacles 18 and 20 are 95 provided with suitable covers 62 and 64, pivoted at 66 and 68 respectively and spring-urged into place by suitable springs 70, provided for the purpose. Each of the four covers enumerated in this and the preceding paragraph can be separately elevated against the action of its controlling spring, as the operator desires, so that he may remove either one of the receptacles 14 or 16, or he may reach into either one of the receptacles 18 or 20.

When casters of this type are used in public places, one each on a plurality of tables, and a waiter or other employee is required to recharge the contents of all of the receptacles, it is a great convenience for him to be able to simultaneously automatically raise

the covers on the four receptacles 14, 16, 18 and 20 and keep them raised until he gets through with this work in hand. This desirable result is accomplished in the device 5 of this invention by the mechanism which will now be described. The base 24 is mounted upon a plurality of collapsible legs 72 which, in the particular case here illustrated, are rendered collapsible by being 10 mounted to slide vertically through the base 24 under the control of springs 76, engaging a cam face 78 on the adjacent leg, and normally locking in terminal notches 80 and 82. These legs 72 are of such a length that 15 when in position shown in Fig. 4, the base 24 and the entire caster is supported clear of the table 84, as shown in Figs. 1 and 2, and that when the whole device is depressed so that the legs 72 are moved upward against 20 the action of the springs 76 until the springs enter notches 82, the base 24 rests flat upon the table 84 or other supporting object, the legs 72 in this position extending above the upper surface of the base 24. Vertically 25 slidable with reference to the central post 22, in the particular case here illustrated inside it, is a rod 86, normally spring pressed downward by a suitable spring device as 88 to the normal position shown in Fig. 2, in 30 which the lower end 86^a extends substantially below the base 24 to a position where it but slightly clears the table 84. Extending from this slidable rod 86 through suitable slots provided for the purpose are arms 35 90 adapted to strike the under sides of the covers 62 and 64, and arms 92 adapted to similarly strike the under sides of covers 50 and 52. The parts just described are so proportioned that when the operator 40 strikes or pushes upon the handle 40 and depresses the whole device so that the base 24 contacts with the table 84 in the manner described, the end 86^a of rod 86 will, of course, strike the table 84 and be forced upward within the post 22, so that the end 86^a 45 is on the level with the bottom of base 24, in so doing the arms 90 and 92 elevate their respective adjacent receptacle covers and hold them elevated as long as the base 24 50 rests upon the table 84. While the parts are in this position the operator can, without touching the covers, fill receptacles 18 and 20 and remove for filling or cleaning receptacles 14 and 16. When the operator has 55 finished his work in this direction, he simply lifts the device off from the table 84 and manually presses each of the legs 72 from the heretofore described changed position to the normal position shown in the drawings, whereupon the parts are all restored to normal position and ready for normal use.

Having thus described my invention, what I claim as new and desire to secure by Letters Patent, is:

1. In a device of the class described, the

combination with a suitable base and a support rising therefrom, a plurality of receptacles mounted around said support, a cover for each of said receptacles mounted adjacent thereto, means normally holding each 70 cover on its receptacle, a rod slidably mounted with reference to the support normally positioned out of engagement with said covers but adapted, when moved into engagement with said covers, to simultaneously move a plurality of them off from their respective receptacles. 75

2. In a device of the class described, the combination with a suitable base and a support rising therefrom, a plurality of receptacles mounted around said support, a cover for each of said receptacles mounted adjacent thereto, means normally holding each 80 cover on its receptacle, a rod slidably mounted with reference to the support, normally positioned out of engagement with said covers but adapted, when moved into engagement with said covers to simultaneously move a plurality of them off from their respective receptacles, said rod in normal position extending below said base, and in its second position, where the covers are removed, being level with the bottom of the base, and means temporarily supporting said base above the table or other support when 90 the parts are in the normal position set forth.

3. In a device of the class described, a suitable base provided with legs normally supporting said base, a substantial distance 100 above a table or the like, means for selectively collapsing said legs so as to bring the base in contact with the table, a rod slidable vertically through the base and having its end in proximity to the table when the base 105 is supported clear thereof by said legs, suitable supporting means rising from the base carrying a plurality of receptacles, independent covers for said receptacles carried by said supporting means, means urging 110 each cover into engagement with its receptacle, and means carried by said rod adapted to counteract said urging mechanism on each of the covers whenever the legs of the device are collapsed, as described. 115

4. In a device of the class described, a base, a leg slidable through the base, a spring mounted in the recess in the base through which the leg slides, a cam surface opposite to and engaged by the spring, so arranged 120 that the spring frictionally locks the leg in either one of two selected extreme positions with reference to the base.

5. In a device of the class described, a suitable base member, a plurality of legs vertically movable through the base member 125 normally extending substantially below it, means detachably locking said legs in each of two extreme positions; in one of which they extend below the base and in the other of 130

which they do not, a suitable supporting device rising from the base, a plurality of receptacles mounted around it, a cover member for each receptacle, a rod vertically 5 slidable in the supporting mechanism, spring mechanism urging said rod downward through the base to a position where its lower end is substantially on the level of the lower ends of the base legs when they 10 support the base in elevated position, means on said rod adapted to engage said cover mechanisms but normally clearing them when the rod is in the normal position just

set forth, the whole being so arranged that when the device is depressed to drive the 15 base legs upward, the rod strikes a flat surface on which the device is placed and simultaneously elevates all of the receptacle covers, for the purposes set forth.

In witness whereof, I have hereunto subscribed my name in the presence of two witnesses.

IVAN JAKLICH.
